UNITED STATES PATENT OFFICE.

BENJAMIN B. BETTS, OF ST. LOUIS, MISSOURI.

GUARD-RAIL MOUNTING.

1,155,993.

Specification of Letters Patent.

Patented Oct. 5, 1915.

Application filed February 23, 1915. Serial No. 9,949.

To all whom it may concern:

Be it known that I, BENJAMIN B. BETTS, a citizen of the United States, and resident of St. Louis, Missouri, have invented certain new and useful Improvements in Guard-Rail Mountings, of which the following is a specification containing a full, clear, and exact description, reference being had to the accompanying drawings, forming a part hereof.

My invention relates to improvements in guard rail mountings, especially designed for the mounting of ends of a guard rail and a running rail wherein said ends of the guard rail are positioned in a plane above the running rail and out of parallelism therewith.

The object of my improvements is to provide a structure formed complete in one piece, which will serve as a chair or wear plate between the rails and sleepers, will prevent canting or tilting of the rails and which will prevent the spreading as well as the creeping of the guard rail relative to the running rail.

With the above object in view, my invention consists in certain novel details of construction and arrangement of parts hereinafter fully described, pointed out in my claims and illustrated by the accompanying drawings, in which:

Figure 1 shows in plan my improved mounting as in use, a portion of the running rail being broken away; Fig. 2 is a longitudinal, sectional elevation of the mounting taken on the line 2—2 of Fig. 1; Fig. 3 is a transverse, sectional elevation of the mounting taken on the line 3—3 of Fig. 1, the running rail not being shown, and Fig. 4 is a transverse, sectional elevation taken on the line 4—4 of Fig. 1, the guard rail not being shown.

Referring by numerals to the accompanying drawings, 5 designates the running rail and 6 the body of the guard rail, which parallels the running rail and the ends 7, one only of which is shown, are bent to stand laterally spaced from the running rail greater distances than the body of the guard rail.

9 designates a sleeper or tie. The running rail, the guard rail and the sleeper are all of common construction, and in their specific constructions form no part of my invention.

My improved mounting consists of a plate

10 having adjacent one end a rail bearing surface 11 and adjacent its other end a rail bearing surface 12, which surface 12 is laterally spaced from the surface 11, is in a plane thereabove and disposed at an oblique angular relationship therewith. At the outer side or margin of the surface 12 is a shoulder 13 and at one of the ends or margins of the surface 12, preferably an angular 60 continuation of the shoulder 13, is a stop 14.

Formed through the mounting, intersecting the shoulder 13 and preferably extending inwardly toward the surface 12 beyond the shoulder is a spike opening 15. At the side or margin of the surface 12 opposite the shoulder 13 is a transverse shoulder 16, paralleling the shoulder 13, and whose opposite portion overhangs the surface 12 forming a recess 17 to receive the margin of 75 the base flange of the guard rail end 7.

By preference the shoulder 16 extends the width of the surface 12 and has adjacent its end reinforcing ribs 18.

At the margin of the surface 11 farthest removed from the overhanging shoulder 16 is a shoulder 19, which is arranged at a right angle to the body of the mounting and extending the width thereof. It is to be noted here that the running rail surface 11 is of 80 greater width than the surface 12 for the guard rail, in order simply to provide increased wearing plate surface between the running rail and sleeper. In this surface 11 I form a number of cavities 20, by which 90 I save material as well as to cause the material surrounding the cavities to chill more rapidly and produce a better wearing surface. In opposition to the shoulder 19 there is a shoulder 21 overhanging the surface 11, to form a recess 22 to receive the base flange of the running rail. This shoulder extends only a portion of the width of the mounting and is braced by a rib 23 extended between the shoulders 21 and 16. 95

Formed through the mounting, intersecting the rib 19 and projecting slightly inwardly beyond the rib is a spike opening 24, and formed through the mounting outside of the surface 12 is a pair of spike openings 105 25. In order to simply save material, I form beneath the surface 12 a cavity 26.

In this mounting I have done away with all removable parts, forming the entire mounting in one piece, as by casting, thereby reducing the structural cost to a minimum with a consequent saving in installa- 110

tion time, as the rails are simply placed in position on this mounting, and the rails and mounting secured to the sleepers by common spikes.

5 When in use the stops 14, engaging the ends of the guard rails, prevent all lengthwise movements, or creeping of the guard rail.

Having thus described my invention, what 10 I desire to secure by Letters Patent of the United States is:

1. A guard rail mounting consisting of a unitary structure, comprising a running rail bearing surface, shoulders upstanding from 15 said surface at each of its side margins, a guard rail bearing surface, located in a plane above, laterally spaced from and non-parallel with the running rail surface, upstanding shoulders at each side margin of the 20 guard rail bearing surface, a stop on the guard rail bearing surface for engagement with a guard rail to prevent longitudinal movement of the guard rail, certain of said shoulders overhanging the rail bearing surfaces for the securing of rail base flanges, and there being spike openings for securing rails to the mounting and the mounting to a 25 sleeper.

2. A guard rail mounting, comprising a 30 unitary structure having a running rail bearing surface, a shoulder paralleling each

side margin of said surface, one of which overhangs said surface to form a recess to receive the base of a running rail, a guard rail bearing surface disposed at an angle 35 to and in a plane above the running rail surface, shoulders paralleling the side margins of the guard rail bearing surface, one of which overhangs said surface, and a shoulder upstanding from said guard rail surface 40 at an angle to the other shoulders to engage the end of the guard rail base to prevent longitudinal creeping of the guard rail.

3. A guard rail mounting comprising a running rail seat and a guard rail seat, the 45 guard rail seat being disposed at an angle to the running rail seat and having contiguous to three of its margins upstanding shoulders to engage the sides and end of the base of a guard rail.

4. A guard rail mounting comprising a rail bearing surface, a shoulder at each side of said surface to bear against the sides of a rail base, and a shoulder arranged to bear 50 against the end of a rail base.

In testimony whereof, I have signed my name to this specification, in presence of two subscribing witnesses.

BENJAMIN B. BETTS.
